(57) **CLAIM**

The ornamental design for a toilet plunger, as shown and described.

DESCRIPTION

FIG. 1 is a top-down perspective view of a toilet plunger in accordance with an embodiment;

FIG. 2 is a front elevation view of the embodiment shown in FIG. 1;

FIG. 3 is a rear elevation view of the embodiment shown in FIG. 1;

FIG. 4 is a right side elevation view of the embodiment shown in FIG. 1;

FIG. 5 is a left-side elevation view of the embodiment shown in FIG. 1;

FIG. 6 is a top-down plan view of the embodiment shown in FIG. 1;

FIG. 7 is a bottom-up plan view of the embodiment shown in FIG. 1; and,

FIG. 8 is a bottom-up perspective view illustrating a portion of the interior of the embodiment shown in FIG. 1.

The broken lines shown in the figures are for the purpose of illustrating portions of the toilet plunger and form no part of the claimed design.

The “unger” shown in dashed line and forming part of the design disclosure is a registered trademark of Unger Marketing International, LLC, and forms no part of the claimed design.
